DESIGN FOR A MOISTENING DEVICE

Bernard G. Klein, Chicago, Ill.

Application March 27, 1936, Serial No. 61,819

Term of patent 3½ years

To all whom it may concern:

Be it known that I, Bernard G. Klein, a citizen of the United States, residing at Chicago, in the county of Cook and State of Illinois, have invented a new, original, and ornamental Design for a Moistening Device, of which the following is a specification, reference being had to the accompanying drawing, forming part thereof.

In the drawing,—

Fig. 1 is a perspective view of a moistening device embodying my design, with the cover in place thereon; and

Fig. 2 is a perspective view of the device with the cover in raised position.

I claim:—

The ornamental design for a moistening device substantially as shown and described.

BERNARD G. KLEIN.
